UNITED STATES PATENT OFFICE.

EDWARD D. GALLAGHER, OF NEW YORK, N. Y., ASSIGNEE TO ANCELL H. BALL AND THOMAS A. BALL, A COPARTNERSHIP TRADING UNDER THE NAME OF BEST & COMPANY, OF NEW YORK, N. Y.

SHOE.

1,152,939.

Specification of Letters Patent.

Patented Sept. 7, 1915.

Application filed January 25, 1915. Serial No. 4,992.

To all whom it may concern:

Be it known that I, EDWARD D. GALLAGHER, a citizen of the United States, residing at New York city, borough of Manhattan, county and State of New York, have invented certain new and useful Improvements in Shoes, of which the following is a clear, full, and exact description.

This invention relates to certain improvements in shoes, and the principal object thereof is to provide shoes which will relieve the strain upon the fore-foot, which occurs with former constructions of shoes and, when occurring, results in the loss of function of the toes.

To relieve the said strain, the shoes of the present invention are made with an arch to extend across the anterior arch of the foot, so that the metatarsal bones are supported and there is no stretching of the ligaments of the plantar surface across the heads of the metatarsal bones. The present improvements also correct the tendency to walk with the weight of the body sustained almost wholly by the inner border of the feet. This is an unnatural position in either standing or walking, as the muscles and sinews of the feet become strained and the arches break down. If one walks almost entirely on the inner borders of the feet, it follows that there is no full development of the muscles and sinews of the outer borders of the feet. The small toe of the foot, in very many cases, is of no actual use and is nearly dormant owing to muscular inactivity.

The shoe of the present invention is built to correct the unnatural method of walking and will give almost instant relief to those who suffer from foot troubles mainly produced and caused by improper shoes.

Further objects of the invention are to provide efficient and practical shoes.

These being among the objects of the present invention, the same consists of certain features of construction and combinations of parts to be hereinafter described and then claimed, reference being had to the accompanying drawings illustrating a suitable embodiment of the invention and in which

Figure 1 is a side elevation of a left shoe; Fig. 2 is an underside view of the same; Fig. 3 is a transverse section, in outline only, on the line 3—3 Fig. 2; Fig. 4 is a similar

section on the line 4—4 Fig. 2; Fig. 5 is a transverse section on the line 5—5 Fig. 1 in the direction of the arrow, showing parts of the upper in elevation. Fig. 6 is an inside view of the inner sole; and Fig. 7 is a view of the tarsus of the foot.

Referring to the drawings, a shoe is illustrated which comprises a foot inclosing portion consisting of an upper 10, a vamp 11, a sole 12 and a heel 13. A line of stitches 14 connects the upper and vamp with the inner sole 15, and a line of stitches 16 connects the welt and sole. The construction of the described parts of the shoe may be in any well known or desirable manner, but the important features of these parts resides in the form and shape thereof; and also in the location of the lines of stitches, particularly those which connect the upper and vamp with the sole, or strictly speaking, the inner sole. The shank 17 of the sole lies between the inner transverse edge 18 of the heel and the inner transverse portion 19 of the forepart of the sole. The shank of the sole is abnormally offset from the inner edges of the forepart of the sole and the heel, and as will be seen by the median line 20 dividing the lines 18 and 19, indicating respectively the inner edge of the heel and the inner transverse portion of the forepart, said line 20 will pass to one side of the longitudinal axis of the shank and heel, but will intersect said axis so as to lie at an angle thereto.

It will be noticed that the inner edge 21 of the shank lies much closer to the dividing line 20 than does the outer edge 22 of the shank, so that on a transverse line across the narrowest portion of the shank 17, the distance between the line 20 and the edge 21 will be in the neighborhood of one-third of the distance along the said transverse line or less. In consequence of this construction, the line of stitches 14 between the upper and the vamp and the welt will, at the inner portion of the shank, be so close to the line 20 that the transverse distance across on the other side of said line will be two or more times as great or less. This construction enables the waist 23 of the shoe to be provided at the inner side of the shoe with an arch portion or platform 24, so that said arch portion or platform is extended abnormally outward relatively to the inner edge 21 of the shank. The said raised arch or platform 24, naturally and without strain,

will balance the foot perfectly and will distribute the weight of the body equally on both sides of the foot, thus causing the muscles at both sides of the foot to be exercised 5 without any undue straining of the tendons at either side and without straining the tendons at the ankle bones.

An important feature of the present invention associated with the above described 10 construction of shoe or the equivalent, resides in an arched formation which extends across the anterior part of the foot. To this end there is located to one side and preferably a little to the rear of the point of location 15 of the big toe joint at 24^a, a transverse arch, hump or convexity 24^b built in the shoe itself. This convexity forms a support for the metatarsal bones indicated at *m* in Fig. 7 which would otherwise drop 20 down and produce a stretching of the ligaments on the plantar surface across the heads of the metatarsal bones. Furthermore, the supporting elevation for the forefoot, furnished by the transverse arch or 25 convexity 24^b, results in a full extension of the toes, inclusive of the great toe, and space for this extension is allowed by the substantially straight inside line at 17^a of the shoe and the broad curving sweep of the 30 outer side of the shoe at 17^b.

The abnormal inward offset of the shank of the sole and the arched, abnormally outset, portion or platform of the waist of the shoe, acting upon the foot in the manner 35 before described throw and hold the foot without strain to such position that the full benefit and advantage of the upward convexity or bulge 24^b in the sole in supporting the metatarsal bones, can be felt and appreciated 40 by the wearer of the shoe; in fact even more so than if only the advantage of said convexity or bulge 24^b was present. Consequently all the parts of the improved shoe work together and in harmony to produce the best results in overcoming foot 45 troubles.

Preferably the sole of the shoe is made of flexible yielding leather, making the shoe 50 substantially non-resisting and allowing full development of the muscles of the foot while walking. Of course in order to produce the transverse arch, hump or convexity 24^b, the leather of the sole is molded to shape, to which end the said leather is 55 ally wet so that it may be molded. The described shoe is preferably formed on a

last which forms the subject of a separate application filed by me on even date here-with.

What I claim is:—

1. In a shoe, a sole having an otherwise unsupported upward convexity or bulge molded in the material thereof at a location which falls under the metatarsal bones, for supporting the latter, in combination with 60 a foot-inclosing portion secured to said sole.

2. In a shoe, the combination of a sole having a shank which is abnormally offset at its outer edge relatively to a straight line which equally divides those transverse 70 portions of the heel and forepart which are directly contiguous to the end portions of said shank, and the inner edge of said shank abnormally offset inwardly relatively to the inner edge of said forepart, said sole also 75 having an upward convexity or bulge formed in the material thereof at a location which falls under the metatarsal bones, for supporting the latter, with an upper foot-inclosing portion secured to said sole and 80 having an arch portion in its waist, which is extended abnormally outward relatively to the inner edge of the shank.

3. A sole having an otherwise unsupported upward convexity or bulge molded in the 85 material thereof at a location which falls under the metatarsal bones, for supporting the latter.

4. A sole having a shank which is abnormally offset at its outer edge relatively 90 to a straight line which equally divides those transverse portions of the heel and forepart which are directly contiguous to the end portions of said shank, and the inner edge of said shank abnormally offset inwardly relatively to the inner edge of said forepart, said sole also having an upward convexity or bulge formed in the material 95 thereof at a location which falls under the metatarsal bones, for supporting the latter.

5. In a shoe, a sole having as an integral part thereof, an upwardly presented convexity or bulge having a transverse dimension sufficient to cause the bulge to underlie a plurality of metatarsal bones, whereby 100 they may be conjointly supported.

Signed at New York, N. Y., this 23rd day of January 1915.

EDWARD D. GALLAGHER.
